UNITED STATES PATENT OFFICE.

LUCIAN A. SHELDON, OF SCHENECTADY, NEW YORK, ASSIGNOR TO GENERAL ELECTRIC COMPANY, A CORPORATION OF NEW YORK.

FLOW-METER.

1,170,195.

Specification of Letters Patent.

Patented Feb. 1, 1916.

Application filed June 3, 1914. Serial No. 842,633.

To all whom it may concern:

Be it known that I, LUCIAN A. SHELDON, a citizen of the United States, residing at Schenectady, county of Schenectady, State of New York, have invented certain new and useful Improvements in Flow-Meters, of which the following is a specification.

The present invention relates to flow meters of the type wherein a U-tube containing a suitable liquid, usually mercury, is connected by pipes to a pressure difference creating device arranged in the main through which the fluid to be metered flows.

In connection with the use of such instruments it sometimes happens that the U-tube is subjected to such an excessive pressure on one side or the other as to force the mercury or other liquid over into the main whereby the same is lost, and the instruments are disabled until the liquid is replaced. An excessive pressure might occur, for example, due to an unusual increase in the rate of flow such as would result from the bursting of a main, or it might occur due 25 to a leak in either the leading or trailing pipe.

The primary object of the present invention is to provide means for preventing the mercury or other fluid from being blown 30 out of the U-tube under the conditions above described.

In carrying out my invention I provide a suitable valve at some point in the connection between the leading and trailing sides 35 of the pressure difference creating device which closes in case excessive pressure occurs and thus prevents the loss of the mercury or other fluid.

As will be obvious an excess pressure is 40 much more liable to occur on the leading side than on the trailing side. If it is desired to guard against an excess pressure on the leading side only, I provide a valve which closes only under such circumstances, while if it is desired to guard 45 against an excess pressure on either side I provide a valve which seats under either circumstance.

Referring to the accompanying drawing 50 wherein I have illustrated certain embodiments of my invention, Figure 1 is a sectional view showing one form of my invention, Fig. 2 is a view of a second form, and Fig. 3 is a diagrammatic view showing a meter connected up with a main.

Referring to the drawing, 3 indicates the casing of the instrument in which is contained the indicating fluid as mercury, the same being designated 4. The instrument shown is of known type and comprises a 60 reservoir 5 with which communicates the leading pipe 6 and from which rises the tube 7 with which communicates the trailing pipe 8. The reservoir 5 and tube 7 form in substance the leading and trailing legs 65 of a U-tube manometer as is well understood. The pipes 6 and 8 connect with any suitable form of pressure difference creating device. In the present instance a nozzle plug 6^a is illustrated. 9 is the usual float 70 which rides on the indicating fluid and 10 designates generally the indicating mechanism.

Communication between the two sides of the pressure difference creating device is 75 controlled by the valve 11 here shown as being arranged between the two legs of the U-tube manometer. The valve, when seated, closes the ports 12. The valve is supported by one end of a lever arm 13 pivoted at 14, 80 the other end of which is attached to a float 15 which rides on the fluid 4. The valve will be moved toward and away from its seat by the float falling and rising due to changes in the fluid level in the well, which 85 in turn depends upon the difference in pressure existing between the two sides of the U-tube. So long as this pressure difference is normal the valve does not seat. In case it becomes excessive, however, the fluid level 90 will be depressed to such a point as to cause the seating of the valve. This prevents further deflection and the blowing out of the indicating fluid. This arrangement guards against an excess in pressure on the leading 95 side only.

While I prefer to arrange the valve as shown and control it by means of a float riding on the indicating fluid, it will be understood that I am not necessarily limited to this arrangement, or to the specific means of control as any means which would respond to excess pressure could be utilized.

The arrangement shown in Fig. 2 is substantially the same as that shown in Fig. 1, 100 except that the valve is arranged to seat whenever an excess of pressure occurs on either side of the instrument. To this end the valve 11^a is controlled as before by the float 15^a, but is provided with seats on op- 110

posite sides thereof as indicated at 16 and 17. By this arrangement the valve will close in case of an unusual pressure on either side of the instrument, as will be obvious.

- 5 In accordance with the provisions of the patent statutes, I have described the principle of operation of my invention together with the apparatus which I now consider to represent the best embodiment thereof; but 10 I desire to have it understood that the apparatus shown is only illustrative, and that the invention can be carried out by other means.

What I claim as new and desire to secure 15 by Letters Patent of the United States, is:—

1. In a flow meter, the combination of a pressure difference creating device adapted to create a pressure difference which bears a definite relation to the rate of flow of the 20 fluid to be metered, a U-tube manometer, pipes connecting the device and manometer, valve means for cutting off communication between the leading and trailing sides of the pressure difference creating device in case of 25 excess pressure on one leg of the manometer, and a float which rides on the indicating fluid and controls said valve means.

2. In a flow meter, the combination of a pressure difference creating device adapted to create a pressure difference which bears a definite relation to the rate of flow of the fluid to be metered, a U-tube manometer, pipes connecting the device and manometer, valve means for cutting off communication 35 between the leading and trailing sides of the pressure difference creating device in case of excess pressure on either leg of the manometer, a float which rides on the indicating fluid, and means connecting the float to 40 said valve means.

3. In a flow meter, the combination of a pressure difference creating device adapted to create a pressure difference which bears a definite relation to the rate of flow of the 45 fluid to be metered, a U-tube manometer, pipes connecting the device and manometer, and valve means arranged between the two

legs of the manometer and controlled by the level of the indicating fluid for cutting off communication between the leading and 50 trailing sides of the pressure difference creating device in case of excess pressure on one leg of the manometer.

4. In a flow meter, the combination of a base member forming a reservoir, a tube rising 55 therefrom, said reservoir and tube forming together the respective legs of a U-tube manometer, a valve controlling communication between the reservoir and the tube, and means controlled by excess pressure on the 60 leading side of the flow meter for closing said valve.

5. In a flow meter, the combination of a base member forming a reservoir, a tube rising 65 therefrom, said reservoir and tube forming together the respective legs of a U-tube manometer, a valve controlling communication between the reservoir and the tube, and means controlled by excess pressure on either 70 side of the flow meter for closing said valve.

6. In a flow meter, the combination of a base member forming a reservoir, a tube rising 75 therefrom, said reservoir and tube forming together the respective legs of a U-tube manometer, indicating fluid therein, a valve controlling communication between the reservoir and the tube, a float which rides on the indicating fluid, and means connecting the float to the valve.

7. In a flow meter, the combination of a 80 base member forming a reservoir, a tube rising therefrom, said reservoir and tube forming together the respective legs of a U-tube manometer, indicating fluid therein, a double faced valve, valve seats arranged 85 above and below the same, a float which rides on the indicating fluid, and a pivoted lever connecting the float to the valve.

In witness whereof, I have hereunto set my hand this first day of June, 1914.

LUCIAN A. SHELDON.
